PIN FOR SECURING CURLS

William M. Reger, Jr., and Phyllis C. Reger,
Saginaw, Mich.

Application May 3, 1943, Serial No. 485,542

1 Claim. (Cl. 132—50)

This invention relates to a pin for use by hair stylists in putting up pin curls in the hair of the human head.

One of the prime objects of the invention is to design a very simple, practical and economical pin for use by beauty operators and others, and which can be formed of metal, wood, plastic or other suitable material.

Another object is to provide a simple and effective pin which eliminates the hair pins at present used for securing formed pin curls and which holds the wound curls firmly in place.

Another object is to design a pin which can be readily handled and which holds the pin curls in place much more firmly than heretofore, one of such pins accomplishing what normally requires two or more hair pins, which does not become snagged or tangled when several are loosely held or stacked together, and which can be easily and economically manufactured, packaged, and marketed.

Other objects and features of the invention will more fully appear from the following description and accompanying drawing, and will be particularly pointed out in the appended claim.

A preferred embodiment of the invention is illustrated in the accompanying drawing in which

Fig. 1 is a side elevational view of a pin constructed in accordance with our invention.

Fig. 2 is a top plan view thereof.

Fig. 3 is an end view, and

Fig. 4 is a view showing the pin in position to secure a pin curl.

Fig. 5 is a side elevational view showing a modified construction.

Fig. 6 is a plan view thereof.

In putting up and securing pin curls at the present time, it is common practice that the hair be first sectioned off, after which the pin curls are wound in the usual manner, and then two or more conventional hairpins are used and necessary to hold the curl in position; inasmuch as there are a considerable number of curls in each coiffure, it will be obvious that a considerable number of hairpins are necessary for each person, and require insertion by the operator, and as these hairpins must be left in place until the curls are "set" it is obvious that they are uncomfortable to the wearer and a source of irritation and annoyance, until the time of removal.

Referring now specifically to the drawing, our pin comprises a relatively thin, preferably tapered

strip 10 formed of plastic or other suitable material, the one end section 11 terminating in a point which is readily insertable in the hair, the opposite end section 12 being formed with a head "B" for convenience in handling by the operator.

5 The center section 13 of the pin is offset for a predetermined length as shown so that it approximately fits the inner diameter of a pin curl "C," shown in Fig. 4 of the drawing, and it will of course be obvious that this offset section can be of any desired length to suit the size of pin curl.

In practice the pin curl "C" is first wound or coiled to shape, after which the sharp end section 11 of the pin is inserted so that the center offset section 13 is disposed underneath the central tuft of hair 14 with the end section 11 overlying the curl on the one side, after which the opposite end section 12 is placed over the curl on the opposite side of the curl, thus the pin spans the diameter of the curl, the tuft of hair 14 anchoring the pin, and the end sections 11 and 12 of the pin firmly holding the curl in position. The offset portion of the pin can be 10 of any desired length to suit the size pin curls desired, and there is no danger of the pin slipping out of the hair after insertion although removal is easily effected by the operator.

In Figs. 5 and 6 of the drawing, we have shown 15 a slightly modified construction in which the pin 10 is provided with humps or raised sections 15, so that when the pin is in the hair, the end sections 11 and 12 will overlie the curl "C" as in the first described construction, while the 20 humps 15 will serve to separate the curl from the tuft of hair 14, these humps also serving to anchor the pin in the hair.

From the foregoing description, it will be obvious that we have perfected a very simple, practical, and convenient pin for securing pin curls and the like.

What we claim is:

A hair pin of the character described comprising, a single, flat body tapered from end to end 45 and of a length sufficient to span a pin curl, a flat head on the pin, an elongated offset section intermediate the length of the pin and adapted to lie beneath the hair within the coiled curl opening, the opposite ends of the pin overlying and 50 pressing against the coiled curl to secure it in coiled position.
